(57) **CLAIM**

The ornamental design for a flat folded ear loop face mask, as shown and described.

DESCRIPTION

FIG. 1 is a front elevation view of a flat folded ear loop face mask showing our new design;

FIG. 2 is a rear elevation view thereof;

FIG. 3 is a top plan view thereof, the bottom plan view being a mirror image thereof; and,

FIG. 4 is a left side view thereof, the right side view being a mirror image thereof.

The broken lines shown in the drawings represent portions of the flat folded ear loop face mask that form no part of the claimed design.
